UNITED STATES PATENT OFFICE

2,488,152

DEVICE FOR ADMITTING PREHEATED SECONDARY AIR INTO FURNACE FIREBOXES

Edward L. Wiedman, Tonawanda, N. Y.

Application July 28, 1945, Serial No. 607,569

1 Claim. (Cl. 110—75)

1

My invention relates to improvements in fuel saving devices, and more particularly to that type designed to preheat air while being introduced into the combustion chamber of a boiler or furnace to cause the preheated air to commingle with the products of combustion and thus facilitate the burning of unconsumed and escaping gases rising from the burning fuel.

The object of my invention is to provide an air-heating device designed to be attached to the door closing the fuel-feed opening in a boiler or furnace so as to project into the combustion chamber of the latter when the door is closed, it being so designed that the air drawn into the device is caused to travel through a circuitous path and to compel the air in its path through the device to come in contact with the maximum heating surfaces and retard the flow of the preheated air therethrough while separating the same into small volumes to assure maximum heating effect.

It is also the object of my invention to provide a device of this kind, the body portion or casing of which can be cast and in which the minimum of machining is required so as to provide a simple and inexpensive device readily installed to the door of the fuel-feed opening of a boiler or furnace or in the wall of the latter so that preheated air is delivered over the burning fuel.

In the accompanying drawings illustrating my invention in what I now consider its most approved form,

Fig. 1 is a central longitudinal section through the device, showing the same applied to the door of a boiler or furnace closing the fuel-feed opening leading to the combustion chamber or fire box.

Fig. 2 is a transverse section taken on line 2—2, Fig. 1, looking toward the right.

Fig. 3 is a transverse section on the same line, looking to the left.

Fig. 4 is a transverse section taken on line 4—4, Fig. 1, looking in the direction of the arrow crossing said line.

Fig. 5 is a transverse section taken on line 5—5, Fig. 1, looking in the direction of the arrow crossing said line.

The device comprises a housing or casing 6 which is preferably cast in two parts 7 and 8, connected together in a manner to be hereinafter described to form a unitary structure.

Medially this housing is cylindrical, as at 9, and at its attaching or outer end it is enlarged, as at 10, to form a bell-shaped terminal, or expansion chamber as it may be termed. The inner or free end of the housing or casing is of

2

bulbous formation and gradually enlarged from the medial cylindrical portion 9. This bulbous portion is designated by the numeral 11 and serves also as an expansion chamber. In the 5 region of this bulbous portion the two parts 7 and 8 of the casing or housing are connected together; part 7 being rabbeted to form a projecting circumferential flange 12 internally screw-threaded and part 8 having an annular flange 13 externally threaded and fastened into the flange 12.

The bell-shaped outer end of the casing is closed by an end wall 14 having a hub 15 and spacing lugs 16 lying in contact with the inner 15 surface of the door 17 closing the fuel-feed opening leading to the combustion chamber of a boiler or furnace in which coal or other similar fuel is used to generate heat. Extending through the door 17 is a pipe 18 which is threaded into the 20 hub 15 of the casing and to the outer end of this pipe an air-inlet head 19 is threaded, it having a chamber 20 in communication with the interior of the pipe 18 and numerous air-inlet openings 21 leading to said chamber. This air-inlet head also 25 serves as a nut to tighten the device against the inner side of the door 17. An air-inlet pipe 22 is also threaded into the hub 15 from the inner side of the casing and this pipe trends lengthwise and axially through the major portion of the casing or housing. Pipe 22 serves as a continuation of pipe 18. A single pipe may, therefore, be substituted for the pipes 18 and 22 so long as it is securely fastened within the end wall 14 of the casing and extends through the door 17 a sufficient distance for attachment of the air-inlet head 19 thereto. The pipes 18 and 22 may, therefore, be considered a continuous air-inlet tube, the outwardly projecting portion of which serves 30 as a means to attach the device to the door 17 or to pass the same through an opening in the wall of the combustion chamber of the boiler or furnace. Broadly considered, the door 17 serves as a portion of the wall of the combustion chamber and, therefore, where hereinafter reference 35 is made to the wall of the combustion chamber, it is to include the door 17.

Cast within the part 8 of the casing at or near its inner end is a bridge member 23 so constructed that air passing through the casing will pass 40 around this bridge member, and in the drawings I have illustrated segmental openings 24 at opposite sides of the bridge member for this purpose. This bridge member is recessed on its outer face and into this recess is threaded or otherwise secured an air-return pipe 25 surrounding

and concentric with the air-inlet pipe 22 and spaced therefrom to form an annular air passage 26 between the two pipes, or tubes as they may also be termed. By reason of its attachment to the bridge member 23, this air-return pipe is closed at its inner end and its outer end is open and terminates in spaced relation to the end wall 14 of the casing. In the enlarged outer end of the casing an annular flange 27 is cast and projecting from the end surface of this flange are heating fingers or elongated nubs 28 which trend outwardly or toward the open end of the air-return pipe 25. These fingers or nubs are spaced apart circumferentially and since they are formed integral with the wall of the casing, they become well heated due to the fact that they are disposed directly over the burning fuel within the combustion chamber. From the inner side of the flange additional heating fingers or elongated nubs 29 project and these also trend toward the open end of the return pipe 25. The fingers 29 are preferably disposed at a greater angle to the axis of the casing than the fingers or nubs 28 and they are staggered with relation to the latter, being positioned in line with the spaces between said fingers 28. The fingers or nubs 29 are, therefore, also in a circular series.

From the outer surface of the bridge member 23 a circular series of heating fingers or elongated nubs 30 extend and they are spaced from the air-return pipe 25, as best shown in Fig. 1. Surrounding the circular series of fingers or nubs 30 is a circular series of heating fingers or elongated nubs 31 which extend inwardly or toward the air-escape end of the device. The fingers or nubs 31 of the series are spaced apart, and spaced outwardly from the butt ends of the latter a circular series of heating fingers or nubs 32 is arranged. These are also spaced apart and staggered with respect to the fingers 30 and 31.

It is to be noted that the free ends of the fingers or nubs 30 terminate in the annular space between the circular series of fingers 31 and 32.

Projecting outwardly from the inner surface of the part 8 of the casing are two circular series of fingers 33, 34 which surround an air-escape area 35 from which preheated air escapes through a circular series of air-escape openings 36 formed in the part 8 of the casing.

To clarify the terms "inwardly" and "outwardly," I consider that end of the device secured to the door 17 and receiving the atmospheric air to be the outer end and the air-discharge or opposite end to be the inner end.

In a device of this general type air is taken in one end, heated, and discharged over the burning fuel at the other end. The natural draft created by the communication established between the combustion chamber and the chimney to which the boiler or furnace is connected creates a current of air through the device. When the fire in the combustion chamber is burning, the device is heated by reason of its being located directly above the burning fuel. Air passing through the device enters the inlet openings in the air inlet head 19, passing thence through the axially-disposed air-inlet pipe or tube formed of the parts 18 and 22 and escaping from its inner end. At this point it enters the larger surrounding air-return pipe or tube 25 and passes through the annular passage 26 between the two pipes or tubes 22 and 25, escaping into the enlarged outer bell-shaped end 10 of the casing, which serves as an expansion chamber for the air thus far heated in its course through the device. The direction

of the passage of air is then again reversed so as to travel in the same direction as the air passing through the air-inlet pipe 22, coming in contact, while being compressed in the restricted end of the bell-shaped terminal or expansion chamber 10, with the two annular series of heating fingers 28, 29, which project inwardly from the annular flange 27 located at the receding portion of the wall of said expansion chamber, the air being thus thoroughly heated and the air current broken up by contact with the considerably augmented heating surface provided by the fingers or nubs 28 and 29. After passing these fingers or nubs the air is further compressed in the medial restricted portion 9 of the casing and retarded in its passage through the device, with the result that a more efficient preheating of the same is assured. After passing through the medial restricted portion of the device, or compression chamber as it may be termed, it again encounters, in successive order, the heating fingers or nubs 32, 31 and 30, which are staggered with respect to each other and are located within a gradually widening portion of the casing so that a complete breaking up of the air current is assured while the air is again under expansion. Again, in passing through this portion of the air current path provided in the device, it comes in contact with a greater augmented heating surface and due to the many fingers or nubs provided and because of the combined superficial areas of these nubs exceeding many times the superficial area of the parts from which they project, a considerably higher temperature is provided for the air as it approaches its region of escape.

After passing through the finger or nub area containing the nubs 32, 31 and 30, the air passes through the segmental openings 24 in the bridge member 23 where the greatest diameter of the bulbous inner end or head of the device is located. The air then in highly heated form passes between the two circular series of fingers 33 and 34 and reaches the air escape area 36 surrounded by said last-mentioned fingers, finally escaping through the air escape openings 36 in the bulbous inner end or head of the device.

It will be apparent from the foregoing that the air in passing through the device is given a circuitous course and that at two points in its course it passes through expansion regions and also through a compression region between the expansion regions. Also by reason of the fact that comparatively long fingers or nubs extend inwardly from the wall of the casing or housing, which latter is thoroughly heated by the burning fuel, these fingers or nubs are likewise heated and preheating contact surfaces are provided greatly exceeding in superficial areas the annular or circular regions from which they project. By reason of the fingers or nubs being staggered with respect to each other, the air currents are divided only to come together again as one body under compression by passing through a restricted area, also by reason of at least one annular series of fingers or nubs being formed on a gradually restricted wall portion prior to passing through a restricted area, the flow of the air through the device is retarded and, therefore, subjected to the high temperature within the device over a longer period of time than would otherwise be possible.

The preheating of the air is greatly increased by reason of the heating fingers or nubs being located at a plurality of regions and especially since two of these regions are located at or near

the air escaping end of the device, where the interior of the device is subjected to greatest heat. As the air escaping from the device comes in contact with the unconsumed products of combustion, these are ignited and thus consumed pass off in the usual manner through the chimney to which the boiler or furnace is connected after having utilized the maximum heat created for the purpose intended.

It will be apparent from the foregoing that my invention is subject to many changes in construction and design without departing from the spirit of the same or sacrificing any advantages thereof while adhering to the scope of the invention as disclosed in the following claim.

What I claim is:

A fuel saving device for furnaces or the like, comprising a tubular casing fastened at one end to the wall of a combustion chamber and projecting inwardly therefrom into said chamber, said casing having its fastened end enlarged to form an expansion chamber and its opposite end enlarged to a lesser degree to form a second expansion chamber, an air-inlet pipe extending axially into said casing from the fastened end thereof and having an air-inlet head outside of said casing through which air enters said pipe, said air-inlet pipe being open at its inner end, an air-

return pipe having a closed end confronting and spaced from the open inner end of said air-inlet pipe and having its opposite end opening into said first-mentioned expansion chamber, two series of heating fingers extending inwardly from the wall of said first-mentioned expansion chamber and having the fingers of one series staggered with respect to those of the other, and heating fingers extending from the wall of said second expansion chamber and staggered with respect to each other, said second expansion chamber having air-escape openings through which the heated air escapes after contact with the various heating fingers within said casing.
